United States Patent Office

Des. 193,258
Patented July 17, 1962

193,258

VENDING MACHINE STAND

Kenneth J. McPhail, 2500 Bathurst St., Apt. 408,
Toronto, Ontario, Canada

Filed Dec. 14, 1961, Ser. No. 67,909

Term of patent 14 years

(Cl. D80—9)

FIG. 1

FIG. 2

FIG. 1 is a front perspective view taken from the top of a vending machine stand embodying my new design; and

FIG. 2 is a rear perspective view taken from the bottom thereof.

I claim:

The ornamental design for a vending machine stand, as shown and described.
